UNITED STATES PATENT OFFICE.

CHARLES A. ABBATH, OF QUINCY, ILLINOIS.

CABINET.

1,112,585.

Specification of Letters Patent.

Patented Oct. 6, 1914.

Application filed September 17, 1913. Serial No. 790,155.

To all whom it may concern:

Be it known that I, CHARLES A. ABBATH, a citizen of the United States, and a resident of the city of Quincy, county of Adams, 5 and State of Illinois, have invented certain new and useful Improvements in Cabinets, of which the following is a specification.

My invention relates to improvements in cabinets and more particularly to a drawer 10 construction for the cabinets, whereby the drawer may be fully withdrawn from the cabinet without danger of tilting and falling, and has for its object the provision of an improved construction of this character 15 which is efficient in use, and strong and durable.

The invention consists in the combinations and arrangements of parts hereinafter described and claimed.

20 The invention will be best understood by reference to the accompanying drawings forming a part of this specification, and in which,

Figure 1 is a perspective view of a cabinet 25 embodying my invention, Fig. 2, an enlarged horizontal section taken immediately under the bottom of a drawer of the cabinet, Fig. 3, a longitudinal section taken through a drawer of the cabinet, and Fig. 4, a trans- 30 verse section of a drawer of the cabinet.

The preferred form of construction as illustrated in the drawings comprises a suitable cabinet 1 having suitable drawer compartments therein adapted to receive the 35 ordinary slidable drawers 2, as will be readily understood. Arranged in each of the drawer compartments is a slidable frame 3 which is provided with longitudinal slots 4 in its sides. A guide block 5 is arranged 40 in each of the slots 4 and is secured in position in casing 1 by means of a bolt 6 extending therethrough and also serving to secure a washer 7 to the top of the block, said washer being of a size to extend over 45 the adjacent portions of the corresponding side of frame 3 to prevent vertical movement of said frame but permit sliding thereof. The inner faces of the sides of frame 3 are provided with longitudinal grooves 8

50 having entry notches 9 at the rear thereof. It will be observed that the notches 9 are arranged at the extreme rear ends of grooves 8 at a distance from the front of frame 3 greater than the length of the drawer 2 and also that the drawer is substantially 55

snug-fit in compartment 1, so that it is impossible to remove or up-set the drawer without completely removing frame 3. As the cabinet illustrated is especially adapted for the retention of hardware, such features are highly desirable. A cross bar 10 is secured to the bottom of the drawer and is provided with tongues 11 at its ends adapted to enter through notches 9 and slide in grooves 8, thus permitting the 60 drawer to slide relatively to frame 3 but preventing the drawer from tilting with respect to said frame. The drawer also carries a stop bar 12 which is adapted to contact with a stop block 13 arranged on 65 a central bar 14 of frame 3, said stop bar and stop block being so positioned that they will engage only after partial withdrawal of the drawer with respect to the frame 3. 70

In use when one of the drawers 2 is withdrawn from its compartment, it first slides on frame 3 until stop bar 12 contacts with stop block 13, whereupon the frame 3 is forced to slide with the drawer and constitutes a support for the drawer when withdrawn from the cabinet. The blocks 5 constitute simple and effective guides for frame 3 and the washer 7 and bolts 6 constitute a strong and durable means for holding the 80 corresponding block 5 in position and also for preventing tilting of the frame 3 under the weight of drawer 2 when withdrawn from the cabinet. The drawer may be removed or attached to frame 3 by inserting or 85 withdrawing tongues 11 through notches 9.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as fall within 90 the scope of the appended claim.

Having described my invention what I claim as new and desire to secure by Letters Patent is:

A cabinet comprising a casing provided 105 with a drawer compartment; a frame slideable in said compartment and having longitudinal grooves in the inner faces of the frame sides, there being entry notches at the extreme inner ends of said grooves; 110

means for limiting the movement of said
slidable frame; a drawer snugly fitting said
compartment and slidable on said frame,
said notches being located at a greater dis-
5 tance from the front of said frame than the
length of said drawer; a cross bar on the
bottom of said drawer at the rear and pro-
vided with tongues sliding in said grooves
and adapted to enter said notches; and stops
10 on said drawer and frame arranged to en-

gage after partial withdrawal of said
drawer, substantially as described.

In testimony whereof I have signed my
name to this specification in the presence
of two subscribing witnesses.

CHARLES A. ABBATH.
